UNITED STATES PATENT OFFICE

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 17,491, dated July 26, 1887.

Application filed June 20, 1887. Serial No. 241,928. Term of patent 3½ years.

To all whom it may concern:

Be it known that I, JULIUS PEGEL, a subject of the Emperor of Germany, residing at Camden, in the county of Camden and State of New Jersey, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a center panel. On the right-hand end is the representation of a bunch of flowers. On the

left-hand end of the panel is the representation of an oval, upon which is represented a bunch of flowers. The whole is surrounded by a floral border, as shown.

What I claim as my invention is—

The design for a rug, consisting of a center panel, on one end of the panel being represented a bunch of flowers, on the other end a bunch of flowers in an oval, the whole surrounded by a floral border, as shown.

JULIUS PEGEL.
